REVETMENT

Harold O. Hoffard, Tacoma, Wash., assignor of one-fourth to Myrie M. Williams and one-fourth to Alfred Cavanaugh, both of Snohomish County, near Arlington, Wash.

Application June 29, 1934, Serial No. 733,074

6 Claims. (Cl. 61—38)

My invention relates to revetments, and to a method of revetting banks against erosion.

A great deal of revetment work is being undertaken in connection with flood control operations. 5 Because there are numerous streams to guard against and many points in each stream where the danger of erosion arises, whether from the banks or from dikes, it is necessary that any revetment be simple and inexpensive. It is further desirable that it be of such character that 10 in the event it be broken or damaged it will be possible to repair and replace damaged parts without undue expense, loss of time, or special equipment. My invention incorporates all these 15 advantages, and in addition provides a simple and inexpensive method of placement, especially to protect the under-water portions of banks.

It is therefore a general object of the invention to provide a revetment and a method of revetting 20 which has the various advantages specified and others. Among further advantages are that the action of stream flow on the revetment is not permitted by the structure of the revetment to gain access to the banks beneath the revetment.

25 Another object is to provide a revetment which can be formed from elements which are readily made, usually locally, and which can be placed by hand labor.

With these and other advantages in mind, as 30 will appear hereafter, my invention comprises the novel revetment as a whole and the novel method of revetting banks, as shown in the accompanying drawing, described in this specification, and as will be more particularly defined 35 by the claims which terminate the same.

In the accompanying drawing I have shown my revetment and the method of placing the same in an illustrative form, thereby illustrating the principles of my invention.

40 Figure 1 is a cross section through a stream and bank, showing the method of placing the revetment.

Figure 2 is a plan view of the same.

45 Figure 3 is a detail plan view of adjacent elements of the revetment, showing the manner of securing the same together.

Generally speaking, my invention contemplates the employment of a series of blocks, preferably of concrete or like material, of a size permitting 50 them to be handled by a man. These blocks may vary in shape, though preferably, because of the functional characteristics and because of the cheapness and ease with which they can be prepared, they are square in shape. Each block is provided with devices whereby it can be secured

to adjacent blocks, so that the whole forms a mat, and in this mat, and constituting one of the distinguishing features of my invention, the blocks are arranged in lines and rows which are placed diagonally, that is to say, at an angle to the direction of stream flow, so that when the mat is in place there will not be presented any continuous line or space in the mat running in the direction of stream flow. As a result the stream flow is broken up by small eddys, and the 10 stream tends to silt in the spaces between blocks rather than to wash out material from between them, so that in the course of a comparatively short time the mat becomes in effect a smooth surface consisting of connected diagonally arranged blocks with the interstices silted in. 15

It is also a distinctive feature of my invention that a method is provided whereby the under-water portion of the banks may be properly protected by such a mat forming an integral extension of the above-water portion, and the whole mat can be constructed conveniently above the water, and then the under-water portion sunk 20 into place.

Referring to the drawing, it will be observed 25 that a number of blocks 1 are provided, which, as indicated, are preferably square in shape. Each of these is provided with securing means, and in this instance each block is provided with a pair of crossed rods 2 terminating at one side of the block in an eye 3, and at the opposite side of the block in a hook 4. When laid in the mat the eyes on two sides of a block are engaged with the hooks at the adjacent sides of the adjoining blocks, and by bending these hooks over the eyes 30 the blocks are secured together. Nevertheless, if a block is broken it can be removed and the hooks bent back sufficiently to allow reengagement of new blocks, thus accomplishing the repair of 35 any broken section of the revetment.

The blocks are placed diagonally, as shown best 40 in Figure 2. They are laid on the above-water portion of the bank of the stream, as high as may be necessary to protect the bank, and when a number of these blocks have been thus laid, they will 45 resist any tendency to pull them along the bank, although guy ropes or cables may be connected to the hooks or eyes as may be necessary to anchor the mat preliminary. Now a raft 5, or any suitable float, may be moored alongside the bank 50 where the mat has been laid, and this will serve to support an integral extension of the mat out over the surface of the water. The outward extension from the margin of the stream will be sufficient that when the mat is permitted to sink it 55

will sink to such extent and extend downward and outward as is necessary to protect the under-water portion of the bank. Thus if the under-water portion be comparatively shallow at one point, the extension of the mat need not be so great as where the bank extends to a deeper portion of the bottom of the stream.

When the extension mat has been laid on the raft 5 to an extent sufficient to protect the under-water portion of the bank the raft is pulled, preferably in a down-stream direction, from under the mat, and this portion of the mat, consisting of blocks all secured together, sinks as a unit and lies along the under-water part of the bank. 10 15 20 25 30 35 40

This may be continued, the mat being laid along the bank above water, and the extension, being formed integrally therewith and connected to the sunken portion, is laid on the raft, and the raft is progressively pulled along, sinking the under-water portion of the mat as the work progresses.

What I claim as my invention is:

1. A revetment comprising a plurality of slightly spaced blocks and means securing each one to all adjoining blocks, to form a flexible mat, said blocks being so disposed, relative to the direction of stream flow, that no continuous line between adjacent blocks is presented parallel to the stream flow.
2. A revetment comprising a plurality of substantially square blocks and means securing each block to but slightly spaced from each adjoining block, to form a mat, said blocks being disposed in lines and rows arranged each at an angle to the direction of stream flow.
3. A flexible revetment mat comprising a plurality of slightly spaced blocks arranged in rows disposed angularly with respect to the stream flow, whereby the intervening spaces between the blocks will form no continuous line parallel to the stream flow, and thus no erosion will occur in such spaces, and means on each block directly interengaged with similar means on each adjacent surrounding block to positively interconnect

in definitely spaced relation all adjacent blocks in the mat.

4. A revetment comprising a plurality of substantially square concrete blocks, two crossed bars embedded in each such block, a bar end projecting centrally from each side of each block and terminating in a connecting loop, and each loop being directly interengaged with a similar loop projecting from the side of the adjacent block, to anchor each block in spaced relation directly to all the adjacent surrounding blocks, thus forming a flexible, integrate mat extending continuously over any desired area, and conforming closely to the stream bed contour.

5. The combination of claim 4, in which the blocks are disposed in rows with their diagonals substantially parallel to the stream flow, the spacing lines running angularly to the stream flow, so that no such line is presented parallel to the stream flow, whereby the stream action will deposit silt to fill the spaces between the blocks, binding them all together into a continuous blanket molded to the profile of the stream bank and bed.

6. A method of revetting stream banks against erosion which comprises providing elemental concrete blocks each having a connecting member at each extremity, progressively assembling the mat by mutually interconnecting each block in spaced relation to each adjacent surrounding block by interengagement of the connecting members, progressively laying the mat as rapidly as formed upon the stream bank, the rows of blocks being disposed so that no continuous line between adjacent rows is parallel to the stream flow, and continuing the assembling and laying steps indefinitely to form a single integrate mat of any desired extent transversely of or parallel to the stream flow, flexing as necessary to conform to irregularities in contour and depth of the stream bank and bed.

HAROLD O. HOFFARD.
